UNITED STATES PATENT OFFICE.

GEORGE W. CROWELL, OF ROGERS PARK, ILL., ASSIGNOR, BY MESNE ASSIGNMENTS, TO THE AMERICAN PAPER BOTTLE COMPANY, OF NEW YORK.

MACHINE FOR ADJUSTING THE ENDS IN VESSELS.

SPECIFICATION forming part of Letters Patent No. 360,951, dated April 12, 1887.

Application filed March 3, 1886. Serial No. 193,914. (No model.)

To all whom it may concern:

Be it known that I, GEORGE W. CROWELL, a citizen of the United States, and a resident of Rogers Park, in the county of Cook and State 5 of Illinois, have invented certain new and useful Improvements in Machines for Adjusting the Ends in Vessels, of which the following is a specification.

My invention relates to an improvement in 10 machines for putting the upper end pieces into vessels, and more particularly into cylindrical paper boxes or bottles, the object of my invention being to provide a machine which will adjust the ends in the boxes with precision and 15 dispatch, and which may be employed in connection with boxes of any dimensions.

A further object of my invention is to construct a machine for this purpose which shall be simple and economical in construction, 20 easily and readily manipulated, and durable and efficient in use; and with these ends in view my invention consists in certain novel features of construction and combinations of parts, as will be hereinafter described, and 25 pointed out in the claims.

In the accompanying drawings, Figure 1 is a view, partly in section and partly in elevation, of my improved machine, the operating-treadle being omitted and the presser-arm 30 shown in its elevated position. Fig. 2 is a detached view showing a portion of my improved machine in elevation, the presser-arm being lowered. Fig. 3 is a plan view thereof. Fig. 4 is a detached plan view of one arm of the 35 lever and dog, and Fig. 5 is a modification.

A represents a metal plate or platform, which is bolted or otherwise secured to a wooden bench, B, adapted to hold the bottles or vessel being treated, the said plate A being provided 40 with a screw-threaded opening, through which extends the upper end of the sleeve C, the latter being formed with a shoulder, a, which fits against the under side of the plate A.

To the sleeve C is connected another sleeve, 45 D, by means of the outwardly-curved plate E, which may be formed integral with or secured to the sleeves, as desired. In the two sleeves C D is nicely fitted a rod or spindle, F, adapted to be vertically moved therein, and having re- 50 movably secured to its upper end the presser-arm G, the latter being provided on its outer

curved end with a small roller or caster, b, secured thereon by means of the screw c.

On the spindle F, between the two vertical sleeves C D, is secured the wheel H, in one 55 side of which is formed a recess for containing the head of the set-screw d, holding it stationary on the spindle. On the opposite side of the wheel is formed a recess, in which is fitted a sliding dog, I, a portion of the outer end 60 thereof being cut away, as shown at g, forming the projecting end h. This outer end of the dog I is preferably rounded or beveled, as shown in Figs. 3 and 4 of the drawings, for a purpose hereinafter described. In the rear 65 end of the dog is formed a recess, in which is fitted the coiled spring K, one end thereof bearing on the dog and the rear end bearing against the spindle F, the tendency of the spring being to constantly force the dog outwardly. To prevent the dog from being pushed out entirely, I form the elongated slot 70 or recess i in the wheel, and on the lower side of the dog form the downwardly-projecting lug k, adapted, when the dog is moved longitudinally, to travel back and forth within the slot or recess i, and by striking the outer end thereof prevent the spring from forcing the dog out of the wheel.

On the spindle F, above the wheel H, and 75 resting thereon, is loosely journaled the sprocket-wheel L, held in position by means of the collar l, pinned to the spindle. With this wheel 80 engages the drive-chain M, which is also connected with another pulley, (not shown,) 85 through which the power is derived to operate the machine.

From the under side and near the periphery of the wheel L depends one or more lugs or pins, m, which, when the dog is pushed 90 back toward the spindle F, passes over the cut-away portion thereof, as shown in Fig. 1 but which, when the dog is forced outwardly, bears against the same, as shown in Fig. 2, and thereby throws the lower wheel, H, into 95 gear with the wheel L, and as the wheel H is held rigid with the spindle F the latter will be revolved therewith.

On the under side of the plate A is found 100 the downwardly-extending arm N, to the lower end of which is pivoted a bell-crank lever, O, one arm, P, of which extends downwardly

and has secured to its lower end a treadle or foot-piece for throwing the parts into gear, as will be hereinafter described, and the other arm, Q, of which extends horizontally and bears on the under side of the wheel H, which latter is preferably convex in form, as shown. The arm Q is provided with a slot or opening, n, through which the spindle F passes, and has its outer end slightly turned up and rounded to conform to the shape of the outer end of the dog I, one corner of the outer end of said arm Q being formed with the shoulder or stop o, against which the dog strikes.

Below the arm Q, and forming a bearing therefor, is the collar R, fitting around the spindle F, which collar is formed with convex shoulders for supporting the arm, the collar in turn being supported on the spring S, coiled around the spindle F and resting on the collar T, pinned to the spindle. To the arm Q is secured one end of a spring, U, the opposite end being secured to the under side of the plate A, the function of which spring U is to raise the arm Q to its normal position after being lowered.

Having now described the construction of my improved machine, I will proceed to set forth its operation.

The end to be inserted in the box is first partially inserted by hand and the box then placed over the presser-arm, the latter passing through the opening in the end, and rested on the plate V, secured to the upper end of the sleeve C, which plate may be made slightly concave for the purpose of reducing the diameter of the end when pressed down therein, and the said end thereby more readily adjusted in the box, as shown in Fig. 5 of the drawings. The foot is then placed on the treadle and the arm P of the bell-crank O pushed forwardly, which operates to lower the arm Q and spindle F, the latter being guided in its vertical movements by the sleeves C and D. By lowering the arm Q the dog I is free to move outwardly, whereby, through the intervention of the pin m, the wheel is thrown into gear with the wheel L and the spindle F and arm G rotated. By lowering the spindle and presser-arm and rotating the same, the end r of the box s is pressed into place and with great accuracy, the roller b on the arm traveling around on the same and pressing it equally on all sides until it rests flat on the plate V. If desired, the roller b may have a spring placed behind it, in order that the roller may have a slight play on the arm to compensate for any irregularities in the shape of the box. Again, if desired, the plate V may be so arranged as to be capable of vertical adjustment, which would allow the end to be inserted at any point within the vessel. By inserting the spring S between the bearing R and collar T, the arm Q, when lowered, will give slightly and will not impart a sudden jar to the foot of the operator, which would otherwise be the case. Again, by virtue of the elasticity of the spring S, the spin-

dle and presser-arm are not held down rigidly, which allows the roller b to readily ride over any irregularities on the end of the box. As soon as the bell-crank is relieved of the pressure of the foot, the arm Q, by virtue of the spring U, is raised and the dog I brought in contact with the outer end thereof and forced inwardly until it strikes the shoulder o, whereupon the pins m, as before described, will ride over the cut-away portion of the dog, and the wheel H and the spindle F thereby stopped from rotating. The arm Q, when raised by the spring U, raises the spindle and presser-arm, whereupon the box, with the end nicely adjusted therein, may be removed.

It will be noticed that as soon as the lever and spindle are moved downwardly a distance equal to the thickness of the outer end of the dog I the latter is forced outwardly and the wheel H immediately thrown into gear and the presser-arm rotated. This arrangement allows the presser-arm to rotate as it is being drawn down in order to gradually set or adjust the end in the box, which, as before stated, is first inserted by hand in a slanting position. If desired, the lever may be allowed a little vertical play on the spindle, in order that the wheel H may be thrown into gear and the spindle revolved before being moved vertically.

By having the presser-arm detachably secured to the spindle, it may be removed and others inserted to fit boxes of different diameters.

The plate E, extending from one sleeve to the other, forms a hood or shield around the sprocket-wheel and connecting mechanism and prevents the operator's clothes from becoming caught therein.

Having fully described my invention, what I claim as new, and desire to secure by Letters Patent, is—

1. A machine for putting the ends into paper boxes or other vessels, consisting of a plate or platform for supporting the box and a rotating arm fitting within the box and bearing on the end, substantially as described.

2. A machine for putting the ends into boxes, consisting of a plate or platform and a vertically-movable revolving arm fitting within the box and bearing on the end, substantially as described.

3. In a machine for putting the ends into boxes, the combination, with a plate or platform for the support of the box, of a spindle having a presser-arm secured thereto, a wheel or pulley loosely journaled on said spindle, and a wheel or pulley tightly secured to the spindle and adapted to be thrown into gear with said former pulley and rotate the spindle and arm, substantially as described.

4. In a machine for adjusting the ends in boxes, the combination, with a spindle having detachably secured at its upper end a presser-arm rotating within the box, of a roller secured on the outer end of the latter for bearing on said end, substantially as described.

5. In a machine for adjusting the ends in

- boxes, the combination, with a plate or platform for supporting the box, of a rotating spindle having detachably secured to its upper end a presser-arm fitting within the box 5 and bearing on the end, a tight and loose pulley journaled on the spindle, and a lever connected with the spindle for raising and lowering the same, and throwing the pulleys into and out of gear, substantially as described.
- 10 6. In a machine for adjusting the ends in boxes, the combination, with a spindle having a sprocket-wheel loosely journaled thereon, said wheel having a pin or pins depending therefrom, of a wheel rigid with the spindle 15 and located directly under the sprocket-wheel, said rigid wheel being provided with a sliding dog which, when pushed outwardly, engages with said pin, and a lever connected with the spindle for forcing said dog out of engagement 20 with the pin, substantially as described.
7. In a machine for adjusting the ends in boxes, the combination, with a plate or platform for supporting the box, of a spindle having a tight and loose pulley journaled thereon, 25 said latter pulley having a pin or pins depending therefrom and the tight pulley formed with a recess containing a spring-actuated sliding dog, a lever connected with the spindle for raising and lowering the same, and having, when the spindle is raised, its end bearing against the dog for holding it out of engagement with said pin, substantially as described.
8. In a machine for adjusting the ends in boxes, the combination, with a platform for supporting the box, of a spindle moving vertically in a sleeve secured to the table, a shield formed integral with said sleeve and having a second sleeve on its lower end, through which 35 the spindle moves, and a presser-arm secured in the upper end of the spindle, substantially as described.
9. The combination, with a spindle, of a sprocket-wheel loosely journaled thereon, and provided with a depending pin, a wheel secured to the spindle and formed with a recess, a dog fitting in the recess, and having a spring back of it for forcing it outwardly in contact with said pin, a portion of the forward end of said dog being cut away to allow the pin to 45 travel over it, and a lever connected with the spindle and adapted to raise the same and simultaneously force said dog inwardly out of contact with said pin, substantially as described.
10. The combination, with a spindle fitting in suitable bearings, of a tight and loose pulley connected therewith, a spring-actuated lever for raising and lowering the spindle and throwing the pulleys into and out of gear, a 50 presser-arm detachably secured to the upper end of the spindle, and a roller secured to the outer end of the arm, substantially as described.
11. In a machine for adjusting the ends in boxes, the combination, with a plate or platform for supporting the box, of a spindle having a presser-arm secured thereto, a spring-actuated lever for raising and lowering the spindle, and a spring-cushion, S, located below the lever, substantially as described.
12. In a machine for adjusting the ends in boxes, the combination, with spindle F, of the presser-arm G, the bell-crank O, sleeve-bearing R, having convex shoulders, collar T, and spring S, substantially as described.

Signed at Rogers Park, in the county of Cook and State of Illinois, this 17th day of February, A. D. 1886.
